HURDLE

Roy Ellis Squire, Huntington Park, Calif.

Application February 7, 1934, Serial No. 710,065

17 Claims. (Cl. 272—59)

My invention relates to a hurdle construction to be utilized in races, preferably running races, and is of a type in which the hurdle bar if struck, may be readily kicked to one side without causing 5 the hurdler to fall.

An object and feature of my invention comprises using a single hurdle post supported on spreading feet and on the top of this post is mounted a single hurdle bar. This bar is pivoted 10 on the top of the post so that it may normally occupy a position across the lane or runway used in a hurdle race, and if struck by a hurdler, will be rotated on its pivot.

A further object and feature of my invention 15 is that the post has a beveled upper edge on each side considered lengthwise of the lane or course of the race so that the hurdle bar may tilt downwardly when rotated on its pivot, the pivot structure being expansible and allowing the bar to 20 swing over on its side if desired. A shoulder on the beveled upper edge of the post limits the rotary movement of the hurdle bar so that it cannot swing across an adjacent lane.

A further feature of my invention is forming 25 the pivot of a flexible cord or cable which is under the tension of a spring, or the like, mounted in the hurdle post. This pivot with the spring is sufficient to hold the hurdle bar in proper operative position to allow this to be tilted on its side 30 or to be rotated on its pivot from a position transverse to the running lane to an inclined position parallel to the running lane.

My invention is illustrated in connection with the accompanying drawing, in which:

35 Fig. 1 is a perspective view of my invention with the bar in hurdling position.

Fig. 2 is an elevation taken in the direction of the arrow 2 of Fig. 1, showing the bar dotted when swung to one side.

40 Fig. 3 is a horizontal section on the line 3—3 of Fig. 2 in the direction of the arrows.

Fig. 4 is a horizontal section on the line 4—4 of Fig. 2 in the direction of the arrows.

Fig. 5 is a vertical section on the line 5—5 of 45 Fig. 2.

In my invention, I employ a hollow post or column 11 which is preferably made by employing two side boards 12, a back board 13, and a front board 14, leaving a hollow central space 15. The 50 post is supported by feet, there being a longitudinal foot 16 which is located in alignment with the back board 13 and below such board. The front foot 17 extends between the side boards 12 at the bottom of the front board 14. The top of 55 the foot forms the bottom of the hollow space 15.

At the top of the post or column, a head or bracket 18 is formed of a block of wood. This has a flat top surface 19 in alignment with the upper edge 20 of the rear board 13 and has an under side 21 engaging the upper end of the front board 14. This bracket fills the space between the side boards 12 and extends rearwardly to the inside face of the board 13. The various boards, the feet and the bracket are preferably nailed together.

The two upper side corners 22 of the member 18 are beveled at the front portion leaving a right angular shoulder 23. The upper edge of each of the side boards 12 is likewise beveled at 24 leaving a right angular shoulder 25. The shoulders 23 and 25 are in alignment. A tension spring 26 is secured to an eye 27 located at the bottom of the back board 13 between the sides 12. A cable 28, or the like, is secured to the upper end of the spring and extends upwardly through vertical perforations 29 in the bracket 18 and also through a perforation 30 in the hurdle bar 31. This bar is illustrated as resting at its lower edge on the flat horizontal surface of the bracket 18 and the upper end 32 of the cable may be knotted or otherwise secured after passing through the bar 31 from its lower to its upper edge.

In the manner of operation of the hurdle, this is set up with preferably one hurdle bar being only of sufficient length for a single lane as used in a hurdle race. The cable 28 forms a vertical pivot for the bar 31 and clamps the end over the bracket sufficiently tight to the bracket so that the projecting portion is held horizontal and in alignment with the bracket 18, and also in the same plane as the foot 17. If a hurdler strikes the bar 31, if this is only a light touch, the bar may turn on its edge without rotating on the pivot formed by the cable 28. However, if the bar is given a sufficient kick to force it to one

side, the bar will slide on the beveled faces 22 and 24 but be held from breaking loose from the post by the cable 28 which is always under tension. The hurdle bar, thus, when turned to one side, may extend at right angles to its position of Fig. 1, that is, longitudinally of the running lane, and with its free end extending in the direction of the runner's movements. The shoulders 19 and 25 form a limit to the side swing of the bar 31. Thus it cannot swing sufficiently far

105 to extend into the lane of the next adjacent runner. Manifestly, to return the bar 31 to its position for another race or for a second jump of the hurdle, it is only necessary to lift the bar, turn it on its pivot which is a loose flexible pivot, 110

and then align the bar with the bracket 18. The back board 13 is formed with a fixed upper section 33 which is nailed to the sides 12 and also to the bracket 18 and is also attached to the sides 12 at their rear edge from the two vertical beads or moldings 34. These form a slot within which is fitted a movable section 35 to the back board. The sections 34 and 35 have a bevel 36. A rotatable spring clip 37 may be attached to the foot 16 at the back and utilized to retain the lower end of the removable section 35 in place. This section has the lower end 27 of the spring attached thereto, therefore, when the section is removed, the faces on the spring may be released so that when the hurdle is not in use the spring is not being continually stretched.

As it is inconvenient sometimes to have a number of separate hurdles for the different lanes in a hurdle race, I may extend the length of the foot 17 to extend entirely across a track or over a number of lanes, and have a post at each lane secured to this foot, such post having its own hurdle board secured and pivoted in the manner described, and illustrated above. Also, some 25 hurdlers prefer having two posts support the hurdle bar, therefore, if desired, I may use a post on which the free end of the bar 31 may rest but the bar is not attached to or held on this post in any manner.

30 Various changes may be made in the details of construction of my invention without departing from the spirit or scope of the appended claims.

I claim:

35 1. A hurdle having a single post, a hurdle bar, a resilient tension means attaching one end of the bar to the post and with the post holding the bar in a horizontal operative position, the said tension means permitting the bar to rotate on the post when struck by a hurdler, the post having a horizontal flat surface at the top to engage the underside of the bar and in cooperation with the tension means retaining the bar in its operative position, the opposite sides of the post being beveled and having stop shoulders, the said bar 40 when rotated being adapted to occupy the inclination of the beveled faces, and stop shoulders to limit the rotation of the bar.

45 2. A hurdle as claimed in claim 1, the hurdle bar having a flat lower edge resting on the flat top of the post, the said tension means being adapted to stretch to permit turning of the hurdle bar on one of the corners of the lower edge of the bar.

50 3. A hurdle having a single hollow post with a bracket at the top having a flat upper surface, a hurdle bar having a flat lower edge, a tension spring secured to the said bar and adapted to retain the bar with its flat lower edge on the upper surface of the bracket with the bar extending horizontally to one side of the post, the said tension spring being adapted to stretch and permit the bar to turn on the axis of the post when struck by a hurdler.

55 4. A hurdle having a single hollow post with a bracket on the top extending to one side of the post, said bracket having a flat horizontal upper surface, a tension spring secured to a cable extending through the bracket, a hurdle bar having a flat lower surface, the said cable being attached to the said bar and supporting the bar in a horizontal position when extended outwardly in alignment with the projecting end of the bracket.

60 5. A hurdle as claimed in claim 4, the upper end of the post having a stop shoulder at right angles to the projecting bracket adapted to form

a limit for the rotation of the bar on the axis of the post when struck by a hurdler.

65 6. A hurdle as claimed in claim 4, the upper end of the post having two beveled surfaces on opposite sides of the bracket with a stop shoulder at the end of each surface, each shoulder being at right angles to the projecting bracket, the said spring being adapted to stretch and permit rotation of the bar on the axis of the post and tilting to conform to the slope of the bevel, the said stop shoulder engaging the bar and limiting the rotating movement.

70 7. A hurdle having a single hollow post with feet on the bottom to support the post in an upright position, a bracket at the upper end of the post having a flat horizontal surface, a tension spring in the post, a hurdle bar having a flat lower surface resting on the flat surface of the bracket, means attaching the spring to the bar to hold the bar extending laterally to one side of the post in a horizontal position.

75 8. A hurdle as claimed in claim 7, the said post being formed of vertical boards with a hollow center space enclosing the spring, the upper end of one of the boards having a stop shoulder to limit the rotation of the bar when struck by a hurdler.

80 9. A hurdle as claimed in claim 7, the post being formed of a plurality of vertical boards formed with a hollow center space enclosing the spring, the upper edge of one of the boards being beveled and the spring being adapted to stretch and permit rotation of the bar on the axis of the post and the downward tilting of the bar to the inclination of the bevel, and a stop shoulder 85 limiting the rotation of the bar.

85 10. A hurdle having a single hollow post formed with a back-board, the lower portion of this board being removable, a channel forming means to engage the sides of the removable section, a spring 90 attached to the removable section, a cable connected to the spring, a hurdle bar resting on the top of the post to which said cable is attached.

90 11. A hurdle having a single post with a flat horizontal top, a hurdle bar, a resilient means 95 attaching the bar to the post to hold the bar horizontally on the top of the post when said bar is in its operative position, said resilient mounting being shiftable to permit rotation of the bar when struck by a hurdler.

100 12. A hurdle as claimed in claim 11, the top of the post being beveled to allow the bar to tilt downwardly when rotated on its support from its operative horizontal position.

105 13. A hurdle comprising a single post having a 110 hurdle bar, a single vertical pivot for said bar, a resilient tension means attached to the pivot and the post to retain the bar horizontally on the top of the post by the downward pull of the tension means when in its operative position, said pivot permitting rotation of the bar when struck by a hurdler.

115 14. A hurdle as claimed in claim 13, the said resilient means being shiftable to permit the outer end of the bar opposite the pivot to tilt downwardly when rotated on its pivot.

120 15. A hurdle having a single post, a hurdle bar, a vertical pivot through one end of the bar, a resilient tension means secured to the pivot 125 and to the post and retaining the bar in a horizontal operative position on the post, the bar being adapted to rotate on its pivot when struck by a hurdler and the said resilient means permitting a movement of the pivot from its vertical 130

position and a downward tilt of the outer end of the bar.

16. A hurdle as claimed in claim 15 and a stop means on the upper end of the post to engage the bar and to limit the rotation of the bar on its pivot.

17. A hurdle as claimed in claim 15, the upper end of the post being beveled on opposite sides to retain the bar at a desired inclination when tilted, and a stop shoulder at each bevel to engage the bar and limit the rotation of the bar.
